UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

BOTTOM LIFTING AND EQUALIZING MECHANISM FOR ROAD GRADERS.

Application filed December 23, 1924. Serial No. 757,677.

To all whom it may concern:

Be it known that I, FRANKLIN E. ARNDT, a citizen of the United States, residing at Galion, in the county of Crawford and State 5 of Ohio, have invented certain new and useful Improvements in Bottom Lifting and Equalizing Mechanisms for Road Graders, of which the following is a specification.

10 This invention relates to road graders, and particularly to the heavy road graders of that character wherein a circle is supported upon draw bars and carries the mold board or scraping blade, there being 15 means whereby the scraper with the draw bars may be raised or lowered so as to regulate the cut of the scraper or lift it entirely off the ground.

In devices of this character the draft bars 20 and the circle are very heavy, and lifting devices of this kind are ordinarily operated by gearing including hand wheels, which are disposed adjacent the operator's station at the rear end of the machine, the 25 construction being ordinarily such that either side of the mold board and the draft bars may be lifted so as to cant the mold board or scraper. The draft bars with the circle and mold board are ordinarily so 30 heavy that considerable power must be expended by the operator in order to lift these parts and adjust them.

The general object of the present invention is to provide means which will assist 35 in the lifting of these parts and which will increase the speed and ease of operation.

A further object is to provide means for 40 equalizing the lift on machines of this character so that the lifting arm will operate just as easily and evenly either in its up or down position or in an intermediate position.

A still further object is to provide in this 45 connection longitudinally extending shafts having lifting arms which are operatively connected to the grader "bottom", provide a manually operable means disposed at the operator's station for rotating either one of said shafts in a direction to cause the 50 lifting or lowering of said arms, and provide in connection with these machines means whereby the pull on the arms is equalized so that the pull is just about

as hard when the arm is up and the blade 55 or mold board is raised as when the blade or mold board is down, and thus do away with the unequal pull which is incident to the use of an arm which moves from a depressed position to a raised position where the pull is excessive at first and then gradually reduced as the blade is raised or is very slight at first and then is gradually increased as the blade is lowered.

Another object is to provide a construction of the character last described where- 60 in the equalizer arms are connected by chains to coiled compression springs so that the coiled springs act to counterbalance and exert a lifting force upon the grader bottom. This construction is such that 70 when the springs are at their greatest tension and, therefore, exerting the greatest force, the leverage exerted by the equalizer arms is the least and as the springs relax their tension the leverage exerted by the 75 equalizer arms is increased so that thus the lifting force exerted by the springs is substantially equalized at all times.

Other objects will appear in the course 80 of the following description.

My invention is illustrated in the accom- 85 panying drawings, wherein:—

Figure 1 is a fragmentary side elevation of a portion of a grading machine showing in elevation the means whereby the 85 blade or mold board is raised and lowered;

Figure 2 is a top plan view of the con- 90 struction shown in Figure 1;

Figure 3 is a section on the line 3—3 of Figure 2;

Figure 4 is a sectional view through the washer 35;

Figure 5 is a view in elevation of the U-bolt which connects the chain to the washer;

Figure 6 is a perspective view of the washer with which the chain connects through the U-bolt;

Figure 7 is a fragmentary section on the same lines as Figure 3 but showing one of 100 the eccentrics fully lowered.

Referring to these drawings, it will be seen that I have illustrated so much of a road grader as is necessary for a proper illustration of my invention, it being under- 105 stood that the grader comprises a support-

ing frame consisting of two longitudinally extending, upwardly arched beams 10. These beams at their forward ends are operatively supported upon an arch, which in 5 turn rests upon the front axle (not shown).

Connected to this front axle in a manner not necessary to describe in detail are draft bars 11 which are angular in cross section, which are operatively pivoted for vertical 10 movement to the front arch, and extend rearward and operatively support the circle 12 to which the scraper blade 13 or mold board is operatively attached. The rear ends of the arched frame bars 10 are extended downwardly and then horizontally, and these horizontal portions of these frame bars are supported upon a rear axle and support 15 an operator's station or platform on which the operator stands in steering the machine, oscillating the circle to oscillate the mold 20 board or scraper blade, and raising or lowering the draft bars to thereby adjust the mold board toward or from the ground.

As previously stated, the object of the 25 present invention is to improve upon the means whereby the draft bars are raised or lowered to thus raise or lower the mold board. The draft bars, the circle and the mold board are relatively heavy and, therefore, power operated means must be provided for vertically adjusting these members. To this end, I mount upon each of the 30 beams 10 in suitable bearing brackets 14 carried thereby the longitudinally extending shafts 15. Each of these shafts at its rear end is provided with a worm wheel disposed within a gear casing (not shown), and operating in connection with these worm 35 wheels is a worm shaft 17 having worms 40 engaging the worm gears 16 within the housings or casings and provided with a hand wheel 18. Thus it will be seen that as the hand wheel is rotated in one direction or the other, the shafts 15 will be rotated in one direction or the other. Each shaft 15 is supported in bearing brackets 14, as previously 45 stated, these bearing brackets being connected by means of a transverse tie bar 19. Each shaft 15 carries at its forward extremity a laterally projecting arm 20. This arm, as illustrated in Figure 3, is slightly curved and is keyed upon the shaft 15, and this arm is operatively connected by links 21 to the draft bars and thus to the circle, as 50 usual in machines of this character.

So far I have described a construction 55 which is commonly found on machines of this general character. Mounted upon each of the shafts 15 is an approximately sector-shaped member 22 which, as illustrated, is skeletal in form and provided with a groove 23 in its edge face. This member constitutes a weight equalizer, and it will be seen that the member comprises a radially 60 extending arm 24 and that the sector-shaped

portion of the member starts from a point 70 relatively adjacent the center of motion of the member, extends out tangentially to a circle concentric to the center of motion, as at 25, and then extends at an angle, this portion 26 being in turn tangential to a circle concentric to the center of motion, and then extends approximately concentrically, as at 27, to said center of motion and joins the extremity of the arm. 75

Pivotedly connected or shackled to the eye Z in the extremity of the arm 24 is a chain 28 or other flexible element, which chain extends through the center of a coiled compression spring 29, the extremity of the chain being connected by means of a U-bolt 30 to a disk 31. This disk or U-bolt washer 31 is formed with apertures 32 for the passage of the U-bolt 30 and also with apertures 33 for the passage of the arms of a relatively long U-shaped yoke 34. The opposite end of the spring bears against a washer or disk 35 having a central hub 36 around which the extremity of the spring fits, this washer 35 being apertured, as at 37, for the 80 passage of the arms of the yoke 34. The extremities of these arms of the yoke are screw-threaded and provided with nuts 38. The bight of the yoke 34 is engaged with the extremity of a brace 39. This brace has a central medial portion 40 which is disposed between the pair of yokes 34, as illustrated in Figure 2, then extends laterally and outwardly at an inclination, and then again straight outward laterally, the extremities 90 of this brace being upwardly curved, as at 41, and notched, as at 42, to receive the bight of the U-shaped yoke 34. This brace 40 is riveted or otherwise connected to brackets 43 which are in turn riveted or otherwise 95 connected to the longitudinally extending beams 10, as illustrated in Figure 2, so that the brace not only connects these beams and acts as a brace therefor but also is fully supported by these brackets 43 from any lateral movement under the strain of the springs. 100

It will be seen that this brace 40 resists, therefore, movement of both of the yokes 34 and holds these yokes against any movement laterally with relation to the longitudinal axis of the machine. It will likewise be seen that when the shafts 15 are oscillated to depress the arms 20, that the sector-shaped members 22 will also be moved outward and downward in the same manner that the arms 20 are and that this will draw upon the chains 28, causing the compression of the springs 29. When, however, the shafts 15 are rotated in a reverse direction 115 to raise the arms 20, the sector-shaped members 22 will also be raised and the springs 29 will assist in raising these members 22 and, therefore, assist in rotating the shaft 15 and raising the arms 20 with the weight 120 of the circle and draw bars attached there- 130

to. It will be understood, of course, that the arms 20 are disposed approximately in the same plane as the arms 14.

It is to be particularly noted that when 5 the arms 24 are depressed that the springs are the most compressed and, therefore, exert their greatest power, but that at this time the point of application of this power of the springs is disposed relatively close to 10 the pivotal center or axis of the sector-shaped members 22. When the arms 24 are in a horizontal position the point of application of the power of the springs is at the point X and thus, though the springs have 15 relaxed in their tension, the leverage has increased, that when the arms 24 have moved upward a few degrees the point of application is at the point Y and still further increased, which compensates for the increasing 20 slackness of the springs, and that when the arm 24 is moving toward its vertical position and the spring is consequently slackening, the leverage is increasing so that though between a point 60° from the up- 25 right position of the arm 24 to a point 30° from the upright position of the arm 24, the spring is very greatly relaxing its tension, yet the lever is correspondingly increasing so that at all points the lifting force exerted 30 by the springs is approximately equalized.

It will be seen that I have provided a construction which equalizes at all times the weight of the parts to be lifted so that there is no sudden lifting and then a very 35 great strain on the mechanism, but that the lift is gradual and that as the work to be done increases, the action of the spring increases. With the ordinary tractor grader it takes considerable effort to lift the blade 40 and its attached parts, but with this spring lift and evener or equalizer the lifting hand wheel may be operated very readily in either direction at increased speed and with much greater ease. In effect the lifting 45 strain is just about the same when the lifting arm 20 is up and the blade is raised as when it is down. Thus the raising or lowering device operates just about as easily and evenly either up, down or in an intermediate 50 position.

I claim:

1. The combination with a supporting frame, a member supported below the frame for vertical movement, means on the supporting frame for vertically shifting the supported member, of means for resisting the last named means including springs mounted upon the supporting frame and operatively connected to the supported 55 member and exerting a lifting force thereon, and means for equalizing the strain on the lifting means in all positions of the supported member.

2. The combination with a supporting 60 frame, a member supported below the

frame for vertical movement, means on the supporting frame for vertically shifting the supported member, of means for resisting the downward movement of the supported member including springs mounted upon 70 the supporting frame and operatively connected to the supported member and exerting lifting force thereon, and means for equalizing the lifting force exerted by springs in all positions of the supported 75 member.

3. The combination with a supporting frame, a member supported below the frame, means on the supporting frame for vertically shifting the supported member in- 80 cluding arms mounted for oscillation in a vertical plane, connections between the arms and the supported member, of counterbalancing springs operatively engaged with the arms and urging them in a direction to 85 lift the supported member, and means automatically increasing leverage applied to the member to be lifted as the springs relax their tension.

4. The combination with a supporting 90 frame, a member supported below the frame, means on the supporting frame for vertically shifting the supported member including arms mounted for oscillation in a vertical plane, connections between the arms and the supported member, of spaced springs operatively supported at one end upon the supporting frame, flexible connec- 95 tions engaged at one end with said springs and at the other engaged with the support- 100 ed member, and means over which said flexible connections pass oscillatably mounted for coincident oscillation with said arms and acting to equalize the lifting force ex- 105 ereted by the springs in all positions of the arms.

5. The combination with a supporting frame, a member supported below the frame, means on the supporting frame for vertically shifting the supported member in- 110 cluding arms mounted for oscillation in a vertical plane, connections between the arms and the supported member, of spaced springs operatively supported at one end upon the supporting frame, flexible connec- 115 tions engaged at one end with said springs and at the other engaged with the supported member, and sector-shaped mem- 120 bers over which the connections pass, said sector-shaped members, each having an out- 125 wardly curved face eccentric to the center of movement of the sector-shaped member, one end of the eccentric face being disposed adjacent the axis of oscillation of the member and the other remote from said axis of oscillation whereby to vary the distance between the flexible connection and the center of motion of the eccentric member to thus shift the point of application of each 130 spring from the center as the springs de-

crease in tension to thereby substantially equalize the strain upon the springs in all positions of the supported member.

6. The combination with a supporting frame, a member supported below the frame, means on the supporting frame for vertically shifting the supported member including parallel shafts mounted for oscillation and having radially projecting arms, connections between said arms and the supported member, coiled compression springs, one for each arm, and supported against movement at one end, equalizing members mounted one on each shaft and having outwardly projecting arms and a face extending from the extremity of the arm upward and inward in an approximate curve to a point nearer to the axial center of the eccentric member, flexible connections mounted upon the extremity of the eccentric member and adapted to be engaged by said approximately curved face, said connections being operatively connected to the free end of the spring, the eccentric members being so arranged with relation to the arms that the springs will be put under tension upon a downward movement of the arms and eccentric members, to lower the supported member and be decreased in tension upon an upward movement of the arms and eccentric members.

7. The combination with a supporting frame, a member supported below the frame, means on the supporting frame for vertically shifting the supported member including shafts having radially projecting arms operatively connected to the supported member, equalizing members mounted upon and rotatable with the shafts, each of said equalizing members being formed to provide an approximately curved face extending from a point adjacent the axis of rotation of said shaft outward in an approximate tangent and then extending outward angularly with relation to the first named portion but at a tangent with relation to a circle concentric to the axis of the eccentric and then extending approximately concentric to said axis, a compression spring supported upon the frame at one end, and a connection attached to the extremity of said eccentric member extending parallel to the spring and being engaged with the free end thereof.

8. The combination with a wheeled supporting frame and a scraper operatively supported below the frame for vertical movement, means on the supporting frame for vertically raising or lowering the scraper, means for assisting the vertical movement of the scraper including eccentric members oscillatably mounted upon the supporting frame, each having an edge face, each edge face starting at a point adjacent the axis of the oscillatable member and ex-

tending outwardly to a point remote therefrom, compression springs mounted upon the supporting frame and held from movement at one end, and flexible connections engaging the end of the eccentric element remote from the axis thereof and operatively connected to the free ends of the springs.

9. The combination with a supporting frame, a member supported below the frame for vertical movement, means on the supporting frame for vertically raising or lowering the supported member including longitudinally extending shafts, an arm on each shaft mounted for oscillation in a vertical plane with the shaft, connections between the arms and the supported member, eccentric members mounted upon the shafts and each having an edge face extending in an approximate curve from a point adjacent the axis of the shaft to a point remote therefrom, springs one for each eccentric member mounted upon the supporting frame, means holding that end of each frame adjacent the corresponding eccentric member from movement and including a yoke around which the spring is coiled, said yoke being operatively engaged with the supporting frame, and a flexible connection extending from the extremity of the eccentric member, through said spring, and operatively engaged with the free end thereof.

10. The combination with a supporting frame, a member supported below the frame for vertical movement, means on the supporting frame for vertically raising or lowering the supported member including longitudinally extending shafts, an arm on each shaft mounted for oscillation in a vertical plane with the shaft, connections between the arms and the supported member, eccentric members mounted upon the shafts and each having an edge face extending in an approximate curve from a point adjacent the axis of the shaft to a point remote therefrom, coiled compression springs disposed transversely of the supporting frame and each associated with one of the eccentric members, a U-shaped yoke operatively engaged at its closed end with the supporting frame and extending through said spring, a disk with which the end of the yoke is engaged and against which that end of the spring adjacent the eccentric member is abutted, a flexible connection attached to the extremity of the eccentric member and extending through said spring, and a disk guided upon said yoke and bearing against the free end of the spring and connected to the flexible connection.

11. The combination with a grader of the character described including parallel supporting beams, a circle, draft bars connected thereto and operatively connected to the forward ends of the supporting beams and a scraper mounted upon the circle, of means

- for raising or lowering the draft bars, circle and blade including longitudinally extending shafts operatively supported upon the supporting beams, manually operable means for rotating said shafts, arms mounted upon the shafts, operative connections between said arms and the draft bars and circle, eccentric members also mounted upon the shafts, each of said eccentric members having a grooved peripheral face, the face extending in an approximate curve from a point adjacent the axis of the shaft to a point remote therefrom, a pair of transversely disposed coiled compression springs, 10 one for each of said eccentric members, a yoke operatively supported at one end upon the supporting frame and operatively engaging that end of the corresponding spring adjacent the eccentric, a flexible connection connected to the extremity of the eccentric member and adapted to bear against the curved face thereof as the eccentric member is moved in a direction to lower the circle and draft bars, and a flexible connection extending through the spring and engaged with the free end of the spring. 15
12. The combination with a supporting frame, a member supported below the frame, means on the supporting frame for vertically shifting the supported member including arms mounted for oscillation in a vertical plane, connections between the arms and the supported member, of means engaged with the arms and yieldingly urging them in a direction to lift the supported member, and means for equalizing the pull exerted by said elastic means in all positions of the supported member. 20
13. The combination with a supporting frame, of a member supported below the frame, means on the supporting frame for vertically shifting the supported member including arms mounted for oscillation in a vertical plane, connections between the arms and the supported member, of means 25 engaged with the arms and yieldingly urging them in a direction to lift the supported member, and means for equalizing the pull exerted by said elastic means in all positions of the supported member. 30
14. The combination with a supporting frame, a member supported below the frame, means on the supporting frame for vertically shifting the supported member including arms mounted for oscillation in a vertical plane, and connections between the arms and the supported member, of means engaged with the arms and yieldingly urging them in a direction to lift the supported member, and means for equalizing the strain of said elastic means in different positions of the supported member. 35

In testimony whereof I affix my signature.
FRANKLIN E. ARNDT.
